UNITED STATES PATENT OFFICE.

WILLIAM ERASTUS WILLIAMS, OF CHICAGO, ILLINOIS, ASSIGNOR TO AMERICAN STEEL
FOUNDRIES, OF CHICAGO, ILLINOIS, A CORPORATION OF NEW JERSEY.

METAL RIM AND DISK WHEEL.

Original application filed July 26, 1920, Serial No. 398,927. Divided and this application filed June 16, 1921. Serial No. 478,029.

To all whom it may concern:

Be it known that I, WILLIAM E. WILLIAMS, a citizen of the United States, and resident of Chicago, in the county of Cook and State of Illinois, have invented certain new and useful Improvements in Metal Rim and Disk Wheels, of which the following is a specification, reference being had therein to the accompanying drawing.

10 This invention relates principally to the construction of the rim and adjacent portions of a metal disk wheel, the construction being that shown in my application Serial Number 398,927, filed July 26, 1920, of which 15 this application is a division. The object is to provide a simple construction that will give elasticity and unusual strength in this portion of a wheel and to secure ease of repair and ready cleaning by having a nearly 20 unbroken surface which can be wiped off quickly when desired.

In the accompanying drawings:

Fig. 1 is a view of a small portion, or sector of the face of a wheel.

25 Fig. 2 is a radial section of the wheel.

Fig. 3 is a section on the line 3—3, Fig. 1, with parts separated.

Fig. 4 is a view in the direction of the arrow of Fig. 3.

30 In these views, 1 designates the main annular portion of a wheel rim having a broad flange 6 projecting obliquely inward with its inner marginal portion bent sharply outward to form a more oblique narrow annular projection 7. Against the flange 6 rests a like-inclined flange 9 of a companion member 2, this latter flange having an oblique edge face fitting the projection 7 and secured to the flange 6 by convex-headed bolts 12 having a square body and engaged by nuts 13.

35 These bolts are non-revolvable in the flange 9 to which they are permanently fixed by swaging over the angles of the bodies as indicated at 15. The bolt holes in the flange 40 are cut away at 16, 17 to receive the portions 15, to avoid shearing strains on the bolts which thus bear pulling strains only, and to facilitate assembling. An inwardly dished wheel disk 3 has its peripheral zone 45 outwardly inclined by reason of this dishing and is bent sharply inward near its margin to form a shoulder supporting the projection 7 and then carried outwardly, with respect to the wheel's center, along the flange 6 to the

rim where it again bends abruptly toward 55 the central load plane, indicated by the line 38, forming a flange 4 which fits the rim part 1. The disk is fixed to the flange 6 by a series of rivets 37.

What I claim is:—

1. A rim composed of a main member and an auxiliary flange member secured to the main member by bolts permanently fixed to said flange member, whereby said flange member and bolts are applied and detached 65 as a unit.

2. A main rim member having an inwardly extending flange inclined to the plane of the wheel and provided with bolt-receiving perforations, of a companion ring member having a similarly inclined inwardly extending flange carrying permanently attached bolts smaller than said perforations through which they pass in securing the two rim members together. 70

3. In a wheel of the class described, main and auxiliary rim members having inwardly projecting flanges fitted together and inclined to the plane of the wheel, the flange of the main member being bent laterally near 60 its margin to fit an inclined edge face of the companion flange. 75

4. A rim composed of a main annular member and a companion annular member, each provided, at some distance outwardly 85 from the central load plane, with an inwardly extending flange inclined outwardly with respect to the plane of the wheel, the flange of the main member having elongated perforations, and a series of bolts fixed to the 90 flange of the companion member and adapted to pass through said perforations and to receive clamping nuts.

5. In a wheel of the class described, a rim consisting of a main portion and a companion flange portion, each portion having a flange extending inwardly with respect to the wheel's center, in combination with a disk secured on the inside of the flange of the main portion, and a series of bolts clamping the 95 disk and flanges together and having rounded heads exposed on the outer side of the rim, with nuts engaging the bolts on the inside of the wheel. 100

6. A rim composed of main and companion parts each having an inwardly extending inclined flange fitting against the other flange, the flange of the companion flange bearing a 105

series of permanently attached bolts passing through larger apertures in the other flange, whereby the parts are readily assembled although the bolts are inclined with respect to 5 their direction of movement in assembling.

7. In a wheel of the class described, a bolted-on flange forming a part of the rim, said flange secured to the main portion of the rim through a series of bolts, and the said 10 bolts firmly fixed in said bolted-on flange by having portions of their bodies swaged into engagement with said flange and the bolt holes in the other flange being materially larger than the bolts which enter them.
- 15 8. The combination with a main rim member and a companion member, each having a

flange extending toward the center of the wheel and obliquely outward with respect to the plane of the wheel, of bolts binding said flanges together, and a wheel disk supporting 20 the inner edges of the inwardly extending flanges and itself extending outwardly from said edges alongside the flanges, to meet the main rim member, thereby supporting it in two different planes.

In testimony whereof I hereunto affix my signature.

WILLIAM ERASTUS WILLIAMS.
